L. M. RABINOWITZ,
EYE FOR GARMENTS,
APPLICATION FILED NOV. 26, 1920.

1,425,897.

Patented Aug. 15, 1922.

Louis M. Rabinowitz Inventor
By his Attorney
Charles A. Wilson

UNITED STATES PATENT OFFICE.

LOUIS M. RABINOWITZ, OF NEW YORK, N. Y.

EYE FOR GARMENTS.

1,425,897.

Specification of Letters Patent. Patented Aug. 15, 1922.

Application filed November 26, 1920. Serial No. 426,340.

To all whom it may concern:

Be it known that I, LOUIS M. RABINOWITZ, residing at New York, in the county and State of New York, have invented certain new and useful Improvements in Eyes for Garments, of which the following is a specification.

This invention relates to improvements in garment fastening devices, and more particularly, to what is known as the "eye" of a well known fastening device, known commercially under the term "hook and eye."

One of the objects of the invention is to provide a new and improved construction of eye, which may be more firmly and securely fastened to the fabric than it has been possible in eyes as hitherto constructed.

Another object of the invention is to provide a construction of eye, wherein the number of parts is minimized, and a stronger device provided than exists in prior constructions.

Other objects and aims of the invention, more or less specific than those referred to above, will be in part obvious and in part pointed out, in the course of the following description of elements, combinations, arrangements of parts and applications of principles, constituting the invention; and the scope of protection contemplated will be indicated in the appended claims.

In the accompanying drawing, wherein I have illustrated a preferred form of embodiment of my invention:

Figure 1 is a plan view of a portion of tape, showing my improved eyes mounted thereon.

Figure 2 is a longitudinal sectional view taken on the line 2—2 of Figure 1, looking in the direction of the arrow; and

Figure 3 is a prospective view of the device.

Similar reference characters refer to similar parts throughout the several views thereof.

Before proceeding with a description of the present invention, it may be well to point out here that the eye, which forms the subject matter of the present invention, is of the class wherein the devices are permanently secured to a ribbon or tape, which ribbon or tape with the eyes thereon, is sold by the yard, or other unit of measure, the tape with the eyes thereon being merely cut off as desired, and said tape being sewed to the garment, making it possible for one or a

number of eyes to be fastened to the garment in a single operation.

Moreover, the tape being of a stronger and more durable material than is usually utilized in the making of garments, and the eyes being permanently fastened thereon, the use of such tape, bearing the eyes, provides a stronger and more durable construction in that the eyes have a firmer anchorage in the tape than they would if they were sewed or riveted directly to the garment fabric.

This class of merchandise is, of course, old and well known in the art, but in eyes as hitherto constructed, they have been made of wire bent to proper form, and then riveted to the tape by separate rivets or eyelets. The object of the present invention is to improve upon this last mentioned type of eye, and to provide an eye having integral fastening means, and to eliminate the usual separate eyelets hitherto utilized.

Referring now to the drawing, the reference numeral 1 denotes a section of ribbon or tape, the same being made of woven fabric, as is usual in this art; and the reference numeral 2 denotes one of the eyelets, with which the tape is usually provided, said eyes being spaced apart so that they may be cut off from the tape, as is desired.

The eyes are formed by suitable dies and are cut out of a strip of material, and each eye at its end portions is provided with integrally formed fastening means, the same comprising a tubular rivet or eyelet portion 3, one end of which can be riveted over, or upset, as shown at 4, the material of the strip between the fastening means being curved or bridged, as indicated at 5, providing a space between the material of the eyelet and the fabric for receiving the end of the hook when the eye is in service.

The bridge 5 is formed of diminished width from each of its integral fastening means towards its middle portion, so that it is narrower at its middle portion than at its ends. This construction facilitates its engagement with the hook and centers the point of engagement between the hook and eye.

It will be noted that a shoulder 6 is formed upon one end of the tubular part 3, and that the material of the tape or ribbon is securely clamped between this shoulder or flange 6 and the shoulder or flange 4 formed by the riveting operation.

It will be also noted that inasmuch as the eyelet is formed of sheet material, the bridge 5 is substantially rectangular in cross-section, thereby providing a structure which 5 will resist material stress to a much greater degree than will the usual wire eyelets now in common use. It is, of course, understood that the eye and tape are formed and assembled automatically by a machine having 10 suitable operative parts and dies, which machine of course forms no part of the present invention.

It will accordingly be seen that I have 15 provided a construction well adapted to attain, among others, all the aims and objects above pointed out, in an extremely simple yet efficient manner, and that I have provided an eye which is of simpler and more efficient construction than has heretofore 20 been marketed.

As many changes could be made in this construction without departing from the scope of the following claims, it is intended 25 that all matter contained in the above description or shown in the accompanying drawing shall be interpreted as illustrative only and not in a limiting sense.

Having thus described my invention what I claim as new and desire to secure by Letters Patent is:

1. A device of the class described, comprising a strip of metal, the end portions of which are provided with integrally formed means adapted for attaching it to textile material, said strip having its intermediate portion outwardly bowed, and of gradually reduced width, the point of maximum reduction substantially coinciding with the point of extreme bowing.

2. A device of the class described, comprising a flat strip of material, the end portions of which have opposed flanges adapted to clamp between them a portion of textile material, said device having an outwardly curved intermediate portion, of reduced width, the point of maximum outward extension of the curved portion coinciding with the point of maximum reduction.

3. A device of the class described, comprising a strip of material, the end portions of which have opposed integrally formed flanges adapted to clamp between them a portion of textile material, said strip having an intermediate outwardly raised bridged portion, said bridged portion being of rec-

tangular cross-section and of reduced width, the point of extreme outward extension of said intermediate portion coinciding substantially with the point of minimum width.

4. The combination with a tape or ribbon 60 of textile material, of a plurality of eyes fastened thereto, each of said eyes having integrally formed attaching means, and an intermediate raised bridge portion of reduced width, the point of maximum reduction corresponding substantially with the point of extreme outward projection of said bridge portion.

5. The combination with a tape or ribbon 70 of textile material, of a plurality of eyes fastened thereto, each of said eyes having integrally formed attaching means, and an intermediate raised bridge portion, said bridge portion being of rectangular cross-section, and of reduced width, the point of extreme 75 reduction coinciding substantially with the point at which the bridge reaches its maximum extension.

6. A device of the class described, comprising a flat strip of material, the end portions of which have integrally formed flanged tubular members, by means of which the device is fastened to a textile material, an intermediate portion of said strip of reduced width being curved and disposed in 85 spaced relation with respect to said strip of textile material, the point of maximum reduction in width of such strip coinciding substantially with the point at which said intermediate portion projects farthest from 90 said strip of material.

7. A device of the class described, comprising a flat strip of material, the end portions of which have integrally formed flanged tubular members, by means of which the device is fastened to a textile material, an intermediate portion of reduced width of 95 said strip being curved and disposed in spaced relation with respect to said strip of textile material, the point of maximum reduction of said intermediate portion coinciding substantially with the point at which the strip is spaced farthest from said textile 100 material.

In testimony whereof, I affix my signature 105 in the presence of two witnesses.

LOUIS M. RABINOWITZ.
